UNITED STATES PATENT OFFICE.

ERNEST H. JACOBS, OF SCHENECTADY, NEW YORK, ASSIGNOR TO GENERAL ELECTRIC COMPANY, A CORPORATION OF NEW YORK.

ELECTRIC SWITCH.

1,331,067.

Specification of Letters Patent. Patented Feb. 17, 1920.

Application filed July 29, 1915. Serial No. 42,643.

To all whom it may concern:

Be it known that I, ERNEST H. JACOBS, a citizen of the United States, residing in Schenectady, county of Schenectady, State 5 of New York, have invented certain new and useful Improvements in Electric Switches, of which the following is a specification.

My invention relates to electric switches 10 and more particularly to the actuating mechanism for such switches.

The object of my invention is to generally improve electric switches and more particularly to provide for electric switches a novel 15 and improved actuating mechanism which is very rugged, compact, having quick breaking characteristics, which has a longer stroke and occupies a smaller space than similar mechanisms heretofore known and 20 which is in many other particulars, to be pointed out more in detail hereinafter, an improvement on previous actuating mechanism of this general character.

The novel features which I believe to be 25 characteristic of my invention will be definitely indicated in the claims appended hereto; the features of construction and mode of operation will be understood by reference to the following description taken in 30 connection with the accompanying drawings which show the preferred embodiments of my invention and in which;

Figure 1 is a side elevation of one form of 35 switch embodying the novel features of my invention, Fig. 2 is a front elevation of my improved actuating mechanism and Figs. 3, 4, and 5 are more detailed views, partly in section, of the actuating mechanism; Fig. 3 showing the mechanism in the position it 40 assumes when the switch is closed, Fig. 4 in the position it assumes when the switch is automatically tripped open and Fig. 5 the position it assumes when the mechanism is reset and ready to close the switch.

In Fig. 1 I have shown my invention embodied in a three phase, triple pole, oil 45 switch in which the three poles 1, 2, and 3 of the switch are supported or mounted on a suitable pipe framework 4. The fixed 50 contacts 5 for each pole of the switch are connected to their respective switch terminals through insulator bushings 6 of well known type. The coöperating movable contacts 5^a for each pole of the switch are

simultaneously moved into and out of engagement with their respective fixed contacts to close and open the circuit, by a novel mechanism to be described. The movable contacts 5^a for each pole are moved by an insulating rod 7 which is pivotally connected 55 at one end to an actuating lever 8, and moved in a straight line by a parallel motion or link mechanism comprising the two sets of paralleling links 9 and 10 and the guide links 11. The guide links are pivoted 60 or fulcrumed to the supporting structure of the switch at one end and to the rear paralleling links 10 at the other end.

Instead of moving the actuating levers 8 by actuating the parallel motion mechanisms 70 about the pivot of their paralleling links 10 as an axis as is the usual practice, I provide means for moving the actuating levers and the parallel motion mechanism as a unit about an axis which is external to the mechanism. This means for moving the parallel motion mechanism as a unit, comprises a mechanism which acts to magnify or multiply a comparatively short movement of the operating lever and cause the parallel motion 75 mechanism to move bodily as a unit and also to act as a parallel motion device. As a result of this novel construction, a short movement of the switch operating lever causes a greatly multiplied path of movement 80 for the contact carrying end of the short actuating levers 8, and thereby a very long stroke mechanism is provided which gives a correspondingly long break for the switch, a quicker extinguishment of the arc, 85 and a switch of greater rupturing capacity. By providing a mechanism which moves the contact carrying end of the actuating levers over a multiplied path of movement, I am 90 able to make the actuating levers 8 much 95 shorter than has been heretofore possible and therefore, I can mount the actuating mechanism for the three poles of the switch within a greatly reduced space thus making a very compact switch.

For moving the parallel motion mechanism corresponding to each pole of the switch as a unit, I provide, as best shown in Figs. 3, 4 and 5, an actuator link or member 12 which is preferably a four cornered 105 or substantially diamond-shaped member. These actuators 12 are movably mounted or fulcrumed at one end or one corner to move

about shafts 13 mounted between shoulders of the supporting structure, the actuators being carried on sleeves 14 movable about the shafts. Pivotally mounted on each actuator link 12 at the end or corner opposite its fulcrum are its respective paralleling links 9 and pivotally mounted on each actuator link at a corner or a point intermediate its ends are its respective paralleling links 10. The actuators, carrying the paralleling links, therefore, provide a means for moving the parallel motion mechanisms as a unit, upon the movement of the actuators about their fulcrums as pivots. The sleeves 14 also carry mounted thereon, arms 15 movable therewith and with the actuator links 12. The arms 15 for each pole of the switch are interconnected by rods 16, best shown in Fig. 1, so that the movement of one actuator 12 or one arm 15 causes the simultaneous movement of all the parallel motion mechanisms to open or close the switch.

For moving the actuator 12 corresponding to the pole 3 of the switch and, therefore, for controlling the whole switch actuating mechanism, I provide an operating mechanism comprising two operating members 17 which are pivotally mounted upon the actuator, at a point intermediate its ends. The operating members or levers 17 are joined or connected at their opposite or free ends by a plate 18. Pivotally mounted upon a shaft between the levers 17 at a point intermediate the ends of the levers, is a link 19, which coöperates with links 20 to form an operating toggle. The toggle links 20 are carried at one end by a sleeve 21 on the operating shaft 22, and are connected at their other ends to the toggle link 19. Lugs 40 or buffers 23 on the links 20 coöperate with corresponding lugs or buffers 24 on the free ends of operating levers 17, for limiting the movement of the toggle in one direction. The operating mechanism for the actuator 12 therefore comprises essentially a three link toggle consisting of the operating toggle 19—20 and levers 17.

Carried on a shaft 25 connecting the toggle links 19 and 20, are arms 26 which, with the pivotally connected latching member 27 form the latching or locking mechanism for the switch. The arms 26 with the latching member 27 move during the operation of the switch between the two operating levers 17 along the plate 18 and are so arranged that when the arms 26 extend a sufficient distance between the levers 17, the latch 27 falls by gravity about its connection to the arms 26 as a pivot and through its recessed or notched portion 28, engages the plate 18 and thus locks the operating toggle to the operating levers and to the actuator 12. To limit the movement of the latch 27 and hold it in alignment with arms 26 when the mechanism is in releasing or un-

locked position, a lug is provided on the latch which coöperates with a pin 29 between the arms 26. For aiding the latching mechanism and maintaining it in latching position and for withstanding the opening thrust of the mechanisms, the arms 26 are provided with a holding or restraining element consisting of a bar 30 connecting the two arms 26 at such a point that as the latch falls into latching position, the bar 30 falls in behind a pin 31 provided between the ends of the operating levers 17 for this purpose. The shaft 25 extends beyond the toggle links 20 and coöperates with lugs or projections 32 on the supporting structure 80 of the switch, as best shown in Fig. 2 to limit the movement of the operating toggle 19—20 to switch closing position and hold it in a slightly overset position.

The tripping mechanism which coöperates with the latching mechanism to move the switch to open position consists of a tripping member 33 in substantially the form of a bell crank which is pivotally mounted on a support attached to the lower end of the supporting structure for the switch mechanism and in operative relation with the latch 27. The tripping member 33 has a weighted arm 34 positioned to normally hold the member 33 out of tripping engagement 95 with the latch 27 and another arm or tripping portion 35 which is slotted and positioned to engage the latch 27 and move the latching mechanism to releasing position. The tripping member 33 is provided with means for moving it into tripping position either in response to the opening movement of the switch by hand or automatically in response to predetermined electrical conditions. For moving the tripping member 33 into 100 tripping engagement with the latch 27 in response to the opening movement of the switch by hand, I provide a tripping arm 36 which is pivotally supported at one end between the toggle links 20 at a point intermediate their ends. The other end of the arm 36 is free and terminates in a notched finger which extends into the slotted portion of tripping member 33 and rests by gravity upon a pin 37. When the operating toggle 19—20 is moved from switch closing position, as shown in Fig. 3 toward switch opening position, the tripping arm 36 is moved with the toggle and by means of the notched end of the arm engaging the 115 pin 37, the tripping member 33 is rocked about its pivot and the tripping portion 35 moved into engagement with the latch 27 to release the same and allow the switch to open in a manner to be described. Continued movement of the operating toggle to the position shown in Fig. 5, causes the notched end of arm 36 to ride over the pin 37 and extend through the slotted portion of member 33.

For moving the tripping member 33 into tripping position automatically in response to the occurrence of predetermined current conditions, such as, an overload above a predetermined amount, I provide suitable relays 38, one corresponding to each phase of the circuit to be protected. These relays are carried by the support for the tripping member 33 and have located above their plungers suitable tripping levers 39 which are arranged to engage the weighted arm 34 and move the tripping member 33 into tripping position. I may provide relays which are instantaneous in response to overload or relays having a definite or inverse time limit depending on the character of the installation. For limiting the movement of the tripping member to tripping position I provide a lug on the tripping member which engages a boss 40 on the top of the relay support. When the tripping member 33 is moved into tripping position, the latch 27 is moved until its notched portion 28 is free from the plate 18 whereupon the bar 30 rides over its pin 31 and the levers 17 are released from the operating toggle 19-20. The levers 17 with actuator 12 carrying the parallel motion mechanism thereby collapses quickly and moves into switch opening position, independent of the operating handle. The toggle link 19 is carried by the levers 17 into switch opening position about the shaft 25 as an axis but the toggle links 20 connected directly to the arm 41 to which is removably attached the operating handle, do not move. Through the interconnecting rods 16 all the actuators with their respective parallel motion mechanisms are moved simultaneously into switch opening position.

The operation of my improved actuating mechanism may be explained as follows: When the switch is closed, the mechanism is in the position shown in Fig. 3. The latching mechanism including the latch 27 is in latching position and the operating levers 17 are held rigidly connected to the operating toggle 19-20 which is in slightly overset position in engagement with the lugs 32, while the toggle consisting of levers 17 and 19 is slightly underset. In Fig. 4 is shown the actuating mechanism in the position it assumes when automatically tripped in response to the relays 38. The rigid connection between the operating levers 17 and the operating toggle 19-20 is broken and the actuator link 12 allowed to move downward about its fulcrum as a pivot, carrying the parallel motion mechanism with it as a unit. The contact carrying end of actuating lever 8 is thereby moved over a long path of movement thus causing a long break between the fixed and movable contacts with the result that the arc formed as the contacts separate, is attenuated and quickly extinguished and a switch of increased rupturing

capacity is produced. The operating levers 17 move into switch opening position without affecting the toggle links 20 so that the mechanism trips free from the handle as has been before described. As the levers 17 move into switch opening position, the latch 27 moves along the plate 18 and is held in rigid alinement with arms 26 by the lug on latch 27 engaging the pin 29 as shown in Fig. 4. In a similar manner the actuating mechanism for the switch trips free from the handle when the switch is opened by hand. In this instance as the operating toggle 19-20 is moved toward switch opening position, the tripping arm carried by the toggle links 20 moves the tripping member 33 into tripping position.

To close the switch, it is necessary to lock the operating toggle to the operating levers 17 and to accomplish this, the operating toggle is moved to the resetting position shown in Fig. 5. As the toggle moves to resetting position, the arms 26 with the latch 27 are moved along the plate 18 between the links 17 until the arms extend far enough to enable the latch to fall into latching position as has been described. As the latch moves into latching position, the buffers 23 and 24 come into engagement and limit the movement of the toggle at the same time acting to hold the latching mechanism in alinement. In this position of the actuating mechanism, the tripping portion 35 of the member 33 extends upward between the arms 26 and in back of the bar 30. With the toggle 19-20 locked to the operating levers 17, the movement of the operating toggle into switch closing position is communicated directly to the actuators 12 at the point of connection of levers 17. It is apparent from Fig. 5 that there is, in closing, really the effect of two toggles in series, the toggle 19-20 and the toggle comprising the actuator 12 and operating links 17 with the toggle members of each pair at substantially right angles, so that, as the sleeve 21 is rotated by the operating handle, to move the operating toggle into switch closing position these two sets of toggles move from a position at substantially right angles to each other to assume a nearly straight line position thus greatly multiplying or magnifying the degree of movement of the operating handle. The actuator 12 is thereby rotated about the shaft 13 and in so rotating moves the corresponding actuators 12 for all the poles of the switch through the interconnecting rods 16 to carry all the parallel motion mechanisms about their axes 18 as a pivot. During the initial movement of the actuators 12, the parallel motion mechanisms are moved bodily and finally the action of the guide links 11 exert their influence and simultaneously with the bodily movement of the parallel motion mechanisms, the mechanisms are ex-

tended under the action of their guide links to move the rods 7 and hence the movable contacts into engagement with their coöperating fixed contacts in a straight line.

5 My invention may be embodied in many other forms than that shown and described and I, therefore, do not wish to be restricted to the precise combination shown but intend to cover by the appended claims all changes 10 and modifications which are within the scope of my invention and will be apparent to those skilled in the art.

What I claim as new and desire to secure by Letters Patent of the United States, is:—

15 1. In an electric switch, the combination with relatively movable coöperating contacts, of a mechanism for moving said contacts into and out of engagement in a straight line, and means for moving said 20 mechanism as a unit about an axis external to the mechanism.

25 2. In an electric switch, the combination with relatively movable coöperating contacts, of an actuating lever operatively related to said contacts, a mechanism for causing one end of the actuating lever to move in a straight line, and an actuator member fulcrumed at one end and adapted to move said mechanism as a unit about said 30 fulcrum.

35 3. In an electric switch, the combination with relatively movable coöperating contacts, of an actuating lever associated with said contacts, an actuator member mounted at one end to move about a fixed pivot, a parallel motion mechanism intermediate said actuator member and said actuating lever and movable as a unit by said actuator member about said pivot, and means for 40 moving said actuator member whereby the end of said actuator lever associated with said contacts moves over a proportionately greater path.

45 4. In an electric switch, the combination with relatively movable coöperating contacts, of an actuating lever associated with said contacts, a parallel motion mechanism for moving said actuating lever, an actuator member fulcrumed at one end for moving 50 said mechanism as a unit about said fulcrum as an axis, and means for moving said actuator member about its fulcrum including an operating member pivotally connected to said actuator member at a point 55 intermediate the ends thereof.

55 5. In an electric switch, the combination with relatively movable coöperating contacts, of an actuating lever operatively related to said contacts, a mechanism for moving 60 said actuating lever and causing the end thereof associated with said contacts to move in a straight line, means for moving said mechanism as a unit about an external axis, latching mechanism for holding said means 65 in switch closing position, and releasing

means for tripping said latching mechanism and allowing said switch to open.

6 An electric switch comprising coöperating fixed and movable contacts, an actuating lever operatively related at one end to said movable contact, a mechanism for moving said actuating lever and causing the movable contact to move in a straight line, an operating mechanism, and means intermediate said first mentioned and said operating mechanisms and operatively related thereto to multiply the movement of said operating mechanism and cause the contact carrying end of said actuating lever to have a long path of movement whereby as the switch 80 opens the arc formed between the contacts is attenuated and quickly extinguished.

7 The combination with the coöperating fixed and movable contacts of an electric switch, of an actuating lever operatively related to said movable contact, a parallel motion mechanism including two parallel links operatively related to said lever, means for moving said mechanism as a unit about an extended axis comprising an actuator member fulcrumed at one end and having one of said parallel links pivotally connected thereto at the end opposite the fulcrum and the other of said parallel links pivotally connected intermediate the 95 ends of said member, an operating mechanism for moving said actuator member about its fulcrum including an operating lever pivotally connected to said actuator member at a point intermediate the ends of 100 said member.

8 In an electric switch, the combination with relatively movable coöperating contacts, of an actuating lever operatively related to one of said contacts, a parallel motion mechanism controlling the movement of said lever, means for moving said mechanism about an external axis including an actuator member fulcrumed at one end thereof, one link of said mechanism pivotally connecting the end of said actuator opposite its fulcrum to a point intermediate the ends of said actuating lever, a second link of said mechanism pivotally connecting the other end of said actuating lever to a point 115 intermediate the ends of said actuator member, said actuator member being adapted to thereby move the contact carrying end of said actuating lever over a path of movement greater than its own path of movement.

9 The combination with the coöperating fixed and movable contacts of an electric switch, of an actuating lever operatively related to said movable contact, a parallel motion mechanism for moving said actuating lever, an actuator member fulcrumed at one end for moving said mechanism as a unit about said fulcrum, an operating mechanism 125 for moving said actuating member about its 130

fulcrum including an operating member pivotally connected to said actuator member at a point intermediate the ends thereof.

10. In an electric switch the combination with coöperating fixed and movable contacts, an actuator member fulcrumed at one end, an actuating lever for moving said movable contact, a parallel motion mechanism for moving said actuating lever including two paralleling links operatively related thereto, one of said paralleling links being pivotally connected to said actuator member at the end opposite its fulcrum and the other of said paralleling links being pivotally connected to said actuator member intermediate the ends thereof, an operating mechanism for moving said actuator member about its fulcrum including a member pivotally connected to said actuator member at a point intermediate the ends thereof.

11. In an electric switch, the combination with an actuating lever, a parallel motion mechanism including two paralleling links operatively related to said lever, means for moving said mechanism as a unit about an axis external thereto including a four-cornered actuator member fulcrumed at one end and having one of said paralleling links pivotally connected thereto at the end opposite the fulcrum, and the other of said paralleling links pivotally connected at a corner intermediate its ends, operating mechanism for moving said actuator member about its fulcrum comprising an operating lever pivotally connected to said actuator member at the corner opposite the pivotal connection of said other paralleling link, and an operating toggle connected to said operating member at a point intermediate its ends.

12. An electric switch comprising coöperating fixed and movable contacts, an actuating lever for moving said movable contact, a mechanism operatively related to said actuating lever to cause said movable

contact to move in a straight line, a movably mounted actuator member fulcrumed at one end for moving said mechanism as a unit about its fulcrum as an axis, an operating shaft, a collapsible operating mechanism for moving said actuator member comprising an operating member pivoted at one end to said actuator member at a point intermediate the ends of said member, and an operating toggle having one link fulcrumed on said shaft and the other link pivoted to said operating member at a point intermediate its ends.

13. An electric switch comprising in combination fixed and movable coöperating contacts, a parallel motion mechanism including two paralleling links for moving said movable contact in a straight line, an actuator member fulcrumed at one end and operatively related to said mechanism for moving said mechanism as a unit about the fulcrum of said member, an operating mechanism for said actuator member including a collapsible three linked toggle pivotally related to said actuator member intermediate the ends thereof.

14. In an electric switch, in the combination with relatively movable coöperating contacts, of an actuating lever associated with said contacts, means for moving said lever in a straight line, an actuator member fulcrumed at one end and adapted to move said member as a unit about an axis external thereto, an operating mechanism for moving said actuator member about its fulcrum into switch closing position comprising two toggles in series, latching means for holding said toggles in switch closing position, one of said toggles being overset and the other toggle underset, and tripping means for releasing said latching means and allowing said toggles to collapse and open the switch.

In witness whereof, I have hereunto set my hand this 28th day of July, 1915.

ERNEST H. JACOBS.

Corrections in Letters Patent No. 1,331,067.

It is hereby certified that in Letters Patent No. 1,331,067, granted February 17, 1920, upon the application of Ernest H. Jacobs, of Schenectady, New York, for an improvement in "Electric Switches," errors appear in the printed specification requiring correction as follows: Page 3, line 124, for the article and word "a pivot" read *pivots*; page 4, line 90, claim 7, for the word "extended" read *external*; and that the said Letters Patent should be read with these corrections therein that the same may conform to the record of the case in the Patent Office.

Signed and sealed this 23d day of March, A. D., 1920.

[SEAL.]

M. H. COULSTON,

Acting Commissioner of Patents.
